UNITED STATES PATENT OFFICE.

THOMAS ELLIOTT, OF BIRMINGHAM, ALABAMA, ASSIGNOR TO CONTINENTAL GIN COMPANY, A CORPORATION OF DELAWARE.

GIN-BREAST LIFT.

Application filed August 24, 1927. Serial No. 215,067.

My invention relates to cotton gins, more particularly to means for lifting the breast of a cotton gin, and has for its object the provision of apparatus of the character designated, which shall be simple of design and easy of manufacture, by means of which the gin breast may be readily and easily lifted by an operator when desired, and which includes automatic safety means for retaining the breast in lifted position as long as required.

A further object of my invention is to provide a gin breast lift with counter-balance means and wherein, once the breast is raised, the counter-balance means exerts a force in a direction to hold the breast in its raised position, requiring the exertion of a greater force to lower it.

As is well known in the art to which my invention relates, it is desirable that a gin breast be lifted whenever the gin is shut down so that the saws shall be out of engagement with the cotton when the gin is again started, obviating the necessity of starting under load. In some cases, it is also desirable to operate only a part of a plurality of gins in a plant and leave the others out of operation, in which case the gin breast of the gin or gins out of operation, is raised to lift the ribs away from the saws and the supply of cotton to that gin is cut off. Again, it is sometimes necessary that the gin breast be lifted while the gin is in operation and that the operator insert his hands into the breast to remove obstructions, rearrange the cotton rolls, which must always be present therein, etc. In such situations, it is extremely important that, once the breast is lifted, it remain in its raised position as long as desired. Very serious accidents incurring the loss of hands and arms, and even the lives of the operators, have occurred where the gin breast has fallen while being worked on by the operator.

Breast lifts, as heretofore known to me, have been difficult of operation and cumbersome to handle; furthermore, the trips or safety catches by means of which the breasts have been held in raised position were liable to get out of order and permit a breast to drop, leading to the serious consequences above referred to. These and other difficulties are overcome by apparatus made in accordance with my invention. Briefly, my invention comprises a pivoted operating

arm, means for transmitting movement from the arm to the gin breast to raise it, the last mentioned means being adapted to rotate about a point on the operating arm so that when the arm is moved in a forward direction the breast is first raised and then begins to lower, and means for arresting forward movement of the operating arm when the breast begins to lower. In addition, I provide counter-balance means which not only aids in raising the gin breast but which is so disposed that once the breast is raised, the counter-balance means exerts a holding effect to maintain the breast in its raised position until a greater force is exerted.

Apparatus embodying features of my invention is illustrated in the accompanying drawings, forming a part of this application, wherein

Fig. 1 is a side elevation of my improved breast lift, showing the gin breast in its lowered position;

Fig. 2 is a view similar to Fig. 1 and showing the breast in raised position; and

Fig. 3 is a front elevation of the breast lift shown in Figs. 1 and 2.

Referring now to the drawings for a better understanding of my invention, I show a fragment of a gin having a frame 10 and a breast 11. The breast 11 is pivotally connected to the frame 10 as by hinge 12 disposed at an upper corner of the breast, so that the breast is held in operative position by its own weight. The gin is provided, as is well understood, with a plurality of saws, indicated by dot and dash lines at 13, and secured to the shaft 14. The saws 13, when the breast in the position shown in Fig. 1, extend within the breast between ribs 16 so as to separate the lint from the cotton seed.

When, for any reason, it is desired to stop operation of the gin, the breast 11 is raised to the position shown in Fig. 2 so that the ribs 16 are clear of the saws 13. With the saws rotating, the gin is then out of operation and the operator may insert his hands into the breast to perform such work as is necessary. It will be obvious, under such conditions, that the breast should remain in its raised position to avoid possible serious injury to the operator.

In order to accomplish the before mentioned desired result, I provide an operating arm 17 secured to a tumbler shaft 18, which latter shaft provides a pivot for the arm 17,

Fulcrumed cross-wise of the operating arm 17 is a floating lever 19, the fulcrum of said lever being provided by a pivot 21 carried by the operating arm 17. One end of the floating lever 19 is pivotally connected at 22 to the lower part of the gin breast 11, while the other end of the lever 19, particularly designated as 23, has connected thereto a spring 24, the latter having its other end 10 secured at 26 to the gin frame. It will be noted that the arm 23 of the lever 19, as viewed in Fig. 1, is upwardly turned with respect to the other arm thereof. The reason for this design of the lever will appear 15 more particularly hereafter.

As seen in Fig. 3, the shaft 18 extends across the front of the gin and may be provided at its opposite end from that viewed in Figs. 1 and 2, with a duplicate mechanism comprising an operating arm 27, a floating lever 28, and a spring 29, the latter three all being arranged to function similarly to the operating arm 17, the lever 19, and the spring 24. The operating arm 17 has attached thereto a lever 31 to provide manual means for raising the gin breast.

It will be seen from a consideration of Figs. 1 and 2 that as the lever 31 is pulled forward the pivot 21 of the floating lever 19 describes an arc having the shaft 18 as its center. It will also be seen that the pivot 22 of the end of the floating lever 19 describes an arc having the pivot 12 as its center. This causes a rotary movement of the floating lever 19 about the moving pivot 21 as a center. As the lever 31 is pulled forward and this forward movement is transmitted to the gin breast, the rotary motion of the floating levers 19 and 28 causes the breast to first be raised and then start to lower. This occurs when its pivot 21 swings forwardly of a plane defined by the axes of the pivots 18 and 22 respectively. The arms 23 of the levers 19 and 28 are so disposed 45 with respect to the other arms that when, in the forward movement of the lever 31, the breast starts to lower, the arms 23 engage the shaft 18, and arrest further movement. This position is shown in Fig. 2. It will 50 be seen from a consideration of Fig. 2 that in its raised position, the gin breast 11 is exerting a force on the floating levers 19 and 28 tending to further rotate them clockwise, which movement is effectually prevented by the arm 23. This feature is very 55 important in that it provides means for automatically holding the gin in its raised position and also necessitates the use of force to start to lower it.

The springs 24 and 29 are so disposed that each exerts a force at all times on the operating arms 17 and 27 which tends to bias them in a forward direction. In the position of the breast shown in Fig. 1, the springs 24 60 and 29 are fully elongated and exert a force

which materially aids the operator in lifting the gin breast. In the position of the gin breast shown in Fig. 2, the springs 24 and 29 are only partially elongated and are urging the arm 23 of the floating levers in a 70 direction which would cause each floating lever to rotate about its pivot 21 and effect a lowering of the gin breast. Inasmuch as this latter movement is prevented by the shaft 18, it will be seen that the gin breast 75 is effectually held in its raised position and that it would require the exertion of force sufficient to overcome the effect of the weight of the gin breast and the tension of the springs 24 and 29 to lower it. From the 80 foregoing, it will be apparent that I have devised an improved gin breast lift which may be readily operated to raise the breast and which, once the breast is raised, effectually holds it in its raised position so that an operator may safely work about the gin 85 without danger to life or limb.

While I have shown my invention in but one form, it will be obvious to those skilled in the art that it is not so limited, but is 90 susceptible of various changes and modifications, without departing from the spirit thereof, and I desire, therefore, that only such limitations shall be placed thereupon as are imposed by the prior art or as are 95 specifically set forth in the appended claims.

What I claim is:

1. The combination with a gin frame having a breast pivoted thereto and held in operating position by gravity, of an operating arm, a floating lever carried by the operating arm and pivoted to the gin breast, and counter-balance means coacting with the operating arm to exert a lifting force on the gin breast while raising it, said floating lever 100 and said counter-balance means being so arranged that the gin breast is held in raised position by gravity and the exertion of force is required to lower the breast.

2. In a gin having a pivoted breast held 110 in operating position by gravity, a tumbler shaft, an operating arm secured to the tumbler shaft, a floating lever fulcrumed cross-wise of the operating arm, a pivotal connection between one arm of the floating lever 115 and the gin breast, whereby when the operating arm is pulled forward the floating lever is rotated about its fulcrum and first raises and then begins to lower the gin breast, a spring associated with the floating 120 lever to urge the operating arm in a forward direction, the other arm of said floating lever being adapted to engage the tumbler shaft and arrest movement of the operating arm and the floating lever when the 125 breast is in its raised position and has begun to lower by reason of rotation of the floating lever about its fulcrum.

3. In a gin, a pivoted breast held in position by gravity, a tumbler shaft extending 130

across the front of the gin, an operating arm secured to each end of the shaft, a floating lever pivoted cross-wise of each operating arm and having one end pivotally connected 5 to the gin breast for transmitting movement of the arm to the breast and vice versa, a spring connected to the other end of each floating lever for counter-balancing the

weight of the gin breast, manual means for moving the operating arms, and means for automatically arresting movement of the operating arm and holding it when the breast is in its raised position. ¹⁰

In testimony whereof I affix my signature.

THOMAS ELLIOTT.
